UNITED STATES PATENT OFFICE.

JAMES R. BINFORD, OF DALLAS, TEXAS.

WINDOW-SHADE GUIDE.

Application filed May 14, 1926. Serial No. 109,008.

This invention relates to new and useful improvements in window shade guides and particularly has to do with guides for window shades in closed automobiles such as 5 sedans and the like.

An object of the invention is to provide a window shade guide that will be simple in construction, nominal in cost and also afford an effective means of attaching the shade 10 to a window in such a manner so as to prevent any flapping or swinging to and fro while in use.

Another object of the invention is to provide a window shade guide of the character 15 described that will guide the lower or free end of the shade, thereby causing the shade to roll up evenly on the roller which eliminates the possibility of tearing or wrinkling the same.

20 A particular feature of the invention resides in the adjustment means which facilitates the application of the guides to various sized windows.

A construction designed to carry out the 25 invention will be hereinafter described together with other features of the invention.

The invention will be more readily understood from a reading of the following specification and by reference to the accompanying drawings, in which an example of the 30 invention is shown and wherein:

Fig. 1 is a perspective view of a set of window shade guides, constructed in accordance with my invention.

35 Fig. 2 is an end view of one of the roller brackets showing a part of the guide rod, and Fig. 3 is a plan view of the same.

In the drawings the numeral 10 designates a suitable window shade, such as is 40 used in closed automobiles, and may have a fringe 11 sewed to its lower portion. The shade is wound upon the usual roller 12 which has its ends journaled in brackets 13 which are mounted at each side of the window at its upper portion.

45 The brackets are suitably fastened to the wall on each side of the window by screws 13', or any other suitable means which pass through apertures provided in the base plate 14 of each bracket. Each base plate has a right angular integral shank 15 which extends outwardly and is formed with a circular head 16 at its outer end. A semi-spherical cap 16' is suitably fastened on the

head. The head has suitable apertures 16^a 55 for receiving the trunnions of the roller 12.

A pair of spaced loops 17 are provided in the shank of the bracket with an intermediate web 18 therebetween. It is preferable to make the base and shank integral having 60 the loops stamped in the shank, however, it is to be understood that the aforementioned parts may be made in any suitable manner.

Vertical guide rods 19 are provided on each side of the window and each is offset 65 at 20 to form an eye 21 at its lower end. The upper portion of the guide rods has a plurality of small upset lugs 22 which are adapted to frictionally engage between the inner surface of the loops and the web portions of the brackets. For holding the curtain in alignment, a strip 23 of suitable material is looped over the guide rods and sewed onto the lower portion of the shade. 70

To equip an automobile, the brackets are 75 first placed in position and securely fastened to the wall at the desired height. The upper ends of the guide rods are inserted between the loops and the web. As 80 the inner surface of the loops is of substantially the same diameter as the guide rods it is evident that the upset lugs will frictionally engage when force is applied to push the rods upward to the desired position.

It is obvious that the rods will be securely 85 held at their upper portion and the lower portion is held by any suitable means such as a screw 24, which is to be received in the eye at the lower portion of the guide rod.

Various changes in the size and shape of 90 the different parts, as well as modifications and alterations, may be made within the scope of the appended claims.

What I claim, is:

1. In a window shade guide, a shade 95 bracket having an outwardly directed loop upon its shank, and a vertical guide rod having a plurality of projections at its upper portion engaging said loop and bent upon itself to form a securing eye at its 100 lower end.

2. In a window shade guide, a bracket formed with an outwardly directed shank having upper and lower loops connected by a web, and a vertical guide rod having a plurality of upset lugs at its upper portion to frictionally engage with the loops and web 105 of the bracket and having its lower end bent

inwardly and to form an attaching eye adapted to be secured in contact with a support.

3. In a window shade guide, a bracket formed with an outwardly directed shank having spaced loops thereon, and a vertical guide rod formed in its upper end with a

series of projections for frictional engagement with the loops and at its lower end with an attaching eye adapted to be secured to a support. ¹⁰

In testimony whereof I affix my signature.

JAMES R. BINFORD.
